UNITED STATES PATENT OFFICE.

MAUD P. TERRELL, OF NEW YORK, N. Y.

DESIGN FOR A LIGHTING-FIXTURE GLOBE.

Application filed March 6, 1928. Serial No. 25,714. Term of patent 7 years.

To all whom it may concern:

Be it known that I, MAUD P. TERRELL, a citizen of the United States, and a resident of New York city, New York, have invented a new, original, and ornamental Design for a Lighting-Fixture Globe, of which the following is a specification, reference being had to the accompanying drawing, forming a part thereof.

Fig. 1 is an elevation showing the profile of a lighting fixture globe embodying the stepped or "set back" motif of my novel design;

Fig. 2 is an inverted plan of Fig. 1.

The design is embodied in a lighting fixture

globe as shown and comprises a series of approximately cylindrical stepped portions which are joined to one another by overhanging portions lying in substantially parallel horizontal planes, the uppermost stepped portion being joined to a roof portion which tapers inwardly and upwardly and terminates in an annular concaved neck portion.

I claim:

The ornamental design for a lighting fixture globe as shown and described.

In witness whereof, I have hereunto signed my name.

MAUD P. TERRELL.
